UNITED STATES PATENT OFFICE.

ANNIE E. CASNER, OF CAMDEN, NEW JERSEY.

TOILET-SEAT COVER.

Application filed April 13, 1928. Serial No. 269,740.

The present invention relates to an improved toilet seat cover, the purpose thereof being to provide a temporary cover, insuring cleanliness and sanitation, and at the same time minimizing the transmission of contagious diseases.

Another purpose is to provide an improved cover constructed of any suitable material preferably paper of a crepe character and of sufficient body to withstand substantial absorption, in conjunction with improved means carried by the cover, rotatably and slidably therewith, to enable the cover to be attached to the seat sufficient to prevent displacement.

It is to be understood that the particulars herein given are in no way limitative, and that while still keeping within the scope of the invention, any desired modification of details and proportions may be made in the construction of the appliance according to circumstances.

The invention comprises further features and combination of parts to be hereinafter set forth, shown in the drawings and claimed.

25 In the drawings:

Figure 1— is a view illustrating the toilet seat cover constructed in accordance with the invention.

Figure 2— is a sectional view through the same, showing how the cover folds over the attaching means.

Figure 3— is a sectional view through the folded over part of the cover, where it slidably receives the attaching means.

Referring to the drawings: 1 identifies the toilet seat cover constructed of any suitable material preferably paper of a crepe character, and which may be any shape or proportion. The cover is provided with an opening 2 corresponding to the shape of an opening in a toilet seat, but of slightly less size in order that the marginal edge on the opening in the cover may overlap the marginal edge of the opening in the toilet seat, thereby insuring against contact with the toilet seat.

The cover though made of paper of a crepe character is designed to be of sufficient thickness to avoid tears and yet at the same time to prevent moisture passing through the cover, dampening it and eventually rupturing the cover and preventing it from tearing through. The cover is folded at 3, and in the fold there

is positioned a covered wire 4, capable of remaining in the fold, the ends 5 of the wire being curved to engage under the seat or behind the hinged seat cover, thereby holding the temporary cover in position.

The wire in the fold is pliable or flexible and may be bent under the seat or in engagement with the hinge or behind the lid to the seat or any part of the hinge is fastened in any suitable manner so as to hold the cover in position. The pliability permits the wire to be adjusted or fitted in any manner suitable to holding the cover in position temporarily. The fold of the cover is secured in position by adhesive material, and the wire 4 is formed with a loop 4^a, which is located in the fold of the cover, preventing the wire from rotating in the fold, as well as preventing the wire from moving longitudinally through the fold. The wire is covered with an insulation to prevent it from scarring the seat or the cover or any part with which it might be engaged.

The invention having been set forth, what is claimed is:

1. A temporary sanitary toilet seat cover comprising a seat cover body having an opening therein substantially corresponding to the ordinary seat opening, said cover body having a folded part connected to the body of the seat cover, a wire mounted in the fold of the folded part, said wire having curved ends, to be bent to engage with the toilet seat or the hinged seat cover.

2. The combination with a toilet seat cover comprising a cover body having a folded part, said folded part being fastened to the body of the seat cover, of a covered wire mounted in the fold of the folded part, said covered wire having curved ends for engaging with the toilet seat or its hinged cover to fasten and retain the toilet seat cover in position.

3. The combination with a toilet seat cover comprising a cover body having a folded part, said folded part being fastened to the body of the seat cover, of a covered wire mounted in the fold of the folded part, said covered wire having curved ends for engaging with the toilet seat or its hinged cover to fasten and retain the toilet seat cover in position, said wire substantially centrally thereof being provided with a loop located within the fold to prevent the wire from rotating ex-

cessively and moving longitudinally through the fold.

4. A temporary sanitary toilet seat cover comprising a seat cover body having an opening therein substantially corresponding to the ordinary toilet seat opening, said cover body having a fold, a wire mounted in the fold and

projecting laterally at each end of the fold, the projecting parts of the wire terminating in means to engage with the toilet seat or hinge of the seat cover. 10

In testimony whereof she affixes her signature.

ANNIE E. CASNER.
